UNITED STATES PATENT OFFICE.

ZEBULON B. SMITH, OF ELIZABETH CITY COUNTY, VIRGINIA.

CAR-REPLACER.

1,109,369.

Specification of Letters Patent. Patented Sept. 1, 1914.

Application filed August 11, 1913. Serial No. 784,181.

To all whom it may concern:

Be it known that I, ZEBULON B. SMITH, a citizen of the United States, residing in the county of Elizabeth City and State of Virginia, have invented new and useful Improvements in Car-Replacers, of which the following is a specification.

This invention relates to a car replacer and has for its object to provide an improved implement by means of which derailed cars may be returned to the track, and which possesses advantages not heretofore found in devices of this character. Among these advantages may be mentioned its simplicity both in design and construction, it being possible to form the device in great part between rolls in long bars and cut the bars into lengths to be afterward finished; the ability to use the replacer on either side 20 of the track, the two sides of the replacer being alike; the employment of a reversible fastening means which may be applied to either side of the replacer to connect the replacer securely to a track rail for holding 25 said replacer in position; means for preventing wheels either flanged or flangeless from leaving the replacer after passing thereonto, and means for connecting two or more replacers endwise or in tandem to provide a 30 temporary track when desired, of greater length than the replacer.

With the above objects in view the invention consists of the novel construction and arrangement of parts hereinafter described, 35 pointed out in the appended claims, and illustrated in the accompanying drawings, in which,

Figure 1 is a plan view of the improved car replacer in position on one rail of a rail-way track. Fig. 2 is a side elevation of the same. Fig. 3 is a longitudinal vertical section of the car replacer. Fig. 4 is a transverse section on the line 4—4, Fig. 1. Fig. 5 is a similar view on the line 5—5, Fig. 1. Fig. 6 is a plan view showing a plurality of car replacers arranged in tandem and connected together, and Fig. 7 is a detail view 45 of the connection.

In the drawings, 10 indicates the body of the car replacer, the sides of which are straight and parallel from one end to the other, said ends being cut off squarely and perpendicular to the sides, so that when desired the ends of similar replacers may abut 50 to form a continuous track as in Fig. 6. The underside of the body 10 is flat and without projections except at one end, which

will be called the forward end, from which end depend two lugs 11 preferably riveted to the body and spaced apart as shown to 60 straddle the head of a rail A when placed in position to replace a car. The forward end of the replacer is preferably bent at an angle to the main portion of the body so as to lie flat upon the rail A when placed thereon, the main portion of the body inclining downwardly from the track to the ground as shown in Fig. 2.

The upper surface of the body 10 is formed or is provided with a central rib 12 70 extending from end to end of the body and having parallel sides as shown, upon the rib 12 the tread of the wheels to be replaced will run. Spaced from said rib and projecting upwardly from the body 10 on each side is a 75 flange 13, said flanges being of equal length with the rib and lying parallel thereto, the upper edges of said flanges however being in a higher plane than the top of the rib as clearly shown in Fig. 2. The forward end 80 of the rib 12 is tapered downwardly at 14 to permit the tread of the wheel running smoothly from the replacer onto the track. One or the other of the grooves 15 between the rib 12 and flanges 13 receives the flange 85 of the wheel as it runs along the rib 12. A suitable distance back from the forward end of the car replacer the ribs 13 are thickened at 16, and through each of said thickened portions is formed a hole countersunk at 17 90 on both the inner and outer sides of said portion through one or the other of which openings is passed a bolt or threaded bar 18 having an enlarged head adapted to fit the inner portion of the countersink 17 and 95 provided on its outer end with a nut 19. Between the nut 19 and the car replacer is a clamping jaw 20 preferably L-shaped in cross-section adapted to extend beneath and engage the head of the rail A and be firmly 100 clamped thereto by the nut 19 for the purpose of holding the car replacer in proper position and prevent lateral movement of the replacer under side strain of the car wheel in 105 passing thereover. The outer countersunk portion 17 is to permit the bolt or bar 18 swinging laterally to clamp the jaw squarely against the rail, and also to permit the bolt being removed from one of the flanges 13 110 and placed in the opening in the other flange. This lateral movement of the bolt or bar is necessary in order that the head thereof may pass above the rib 12.

In use the rear end of the replacer is placed against the wheel of the car to be returned to the track and pushed thereunder as far as possible, the rib 12 and one of the 5 grooves 15 alining with the tread and the flange of the wheel, respectively. After which the opposite or forward end of the car replacer is placed on the track, as in Fig. 1, with the lugs 11 straddling the head 10 of one of the rails A. The clamping jaw 20 is moved into position against the head of the rail and the nut 19 screwed up tightly, thereby firmly securing the replacer in position so that the car wheel may travel along 15 the same to the track.

It is to be noted that the two sides of the car replacer are alike and that the rib 12, flanges 13 and groove 15 all lie parallel. Furthermore the bolt or threaded bar 18 20 with its clamping jaw 20 may be employed on either side of the car replacer, thus enabling the implement being used on either side of the track and avoiding the expense and trouble of providing two different devices for the purpose. By making the 25 flanges 13 project above the rib 12, flangeless wheels traveling along the rib are prevented by said flanges from running off the replacer, and for the same reason should a 30 flanged wheel ride up on the rib 12, the projecting flanges 13 would retain said wheel on the replacer as said flanges extend sufficiently high for the purpose.

On some occasions it may happen that the 35 car replacer is not sufficiently long for the purpose desired, but owing to the peculiar construction of the majority of car replacers, it is not possible to place two or more of them in line to form a temporary 40 track. In the present invention however owing to the similarity of both ends of the replacer, any number of them may be placed in line with their ends abutting as shown in Fig. 6, and by providing laterally projecting 45 lugs 21 near these ends and forming holes in said lugs they may be kept connected together by inverted U-shaped links 22, the downwardly projecting legs of which enter the openings in the lugs 21. When so connected the wheels may pass readily from one 50 replacer to the other with little or no jar and without danger of running off.

What I claim is:—

1. A car replacer comprising a body 55 formed on its upper face with a central longitudinal rib for the tread of a wheel, said rib having parallel sides and extending from end to end of the body, a flange projecting from the body on each side of said 60 rib above the top of the rib and parallel therewith, said flanges being as long as the body and spaced from the rib sufficiently far to form parallel grooves for the wheel

flanges, a pair of spaced lugs depending from the under side of said replacer at one 65 end to engage the head of a track-rail on each side and lock said end of the replacer to said rail against lateral displacement in either direction, and a removable clamp adapted to be swiveled to either flange of 70 said replacer and engage the head of the track-rail for holding said replacer in proper relation to the track-rail.

2. A car replacer comprising a body 75 formed on its upper face with a central longitudinal rib for the tread of a wheel, having parallel sides and extending from end to end of the body, and a flange projecting from the body on each side of said rib above the top of the same and parallel with said 80 rib, said flanges being spaced from the rib sufficiently far to form parallel grooves for the wheel flanges, said replacer being adapted to be applied on either side of the track rail, spaced lugs on the underside of said replacer at one end to engage the head of a rail, a bolt or threaded bar adapted to extend through an opening in either flange, and a clamping jaw on said bolt or bar adapted to engage the track rail. 90

3. A car replacer comprising a body 95 formed on its upper face with a central longitudinal rib extending from end to end of the body having parallel sides of equal height throughout its length, and a flange projecting from the body on each side of said rib above the top of the same and parallel with said rib, said flanges being spaced from the rib sufficiently far to form parallel grooves for the wheel flanges, spaced lugs 100 on the underside of said replacer at one end to engage the head of a track rail, and a fastening lug on each side of the replacer near each end provided with a hole adapted to receive a fastening device. 105

4. A car replacer comprising a body having a central longitudinal rib on its upper face and a flange on each side of said rib spaced therefrom and projecting above the surface of said rib, said rib and flanges 110 extending parallel with each other from end to end of the body, a lug on each side of the body near each end provided with a hole adapted to receive a fastening device whereby said car replacer 115 may be joined at each end to similar car replacers to form a continuous temporary track.

In testimony whereof I have hereunto set my hand in presence of two subscribing witnesses. 120
